JOHN P. MINTON
BY *Frank Adams*
ATTORNEY

UNITED STATES PATENT OFFICE

JOHN P. MINTON, OF WHITE PLAINS, NEW YORK, ASSIGNOR TO RADIO CORPORATION OF AMERICA, A CORPORATION OF DELAWARE

LOUD SPEAKER

Application filed June 25, 1925. Serial No. 39,583.

The invention concerns an acoustic device particularly adapted to loud speakers for radio receivers or electric phonographs and has for its principal object to replace the usual diaphragm and amplifying horn of such a device with a vibrating element of sufficient size to set in motion a column of air large enough to make the use of a horn or other amplifying means unnecessary.

10 A further object of the invention is to provide an acoustic device of this character in which the vibrating element will respond readily even to the lowest frequencies within its range of operation.

15 Still another object of the invention is to provide a vibratory system in which the vibratory element will freely vibrate substantially as a piston for the lower frequencies within its operating range and as a diaphragm for the higher frequencies, thereby giving more uniform response throughout its range.

20 Still another object of the invention is to provide a vibratory system in which the vibratory element will freely vibrate at frequencies whose wave lengths are large compared with the size of the element itself so that all of its parts vibrate substantially in phase and with equal amplitude and which at higher frequencies will vibrate as a diaphragm.

25 Still another object of the invention is to provide an acoustic device whose vibrating element is supported by springs or other devices having just enough tension to return it to and maintain it in normal rest position when not subjected to any operating forces.

30 It has been found that the use of suitable diaphragms of large area in acoustic or electro-acoustic devices makes it unnecessary to provide a horn or other sound amplifying means as the large column of air set in motion by such a diaphragm furnishes sufficient acoustic energy to make amplification unnecessary. The large diaphragm moreover,

35 has an advantage over the small one in that there is less interference between the sound waves from its two sides. A vibrating diaphragm, of course, emits sound waves from its opposite sides which are out of phase with each other and as these waves spread out in

all directions those from one side cause interference with those from the other, resulting in considerable diminution and distortion of the sound. A large diaphragm will evince this characteristic to a much less extent than 35 a small one and as a result give more intense radiation with less distortion. These effects are further reduced according to the invention by surrounding the diaphragm with a baffle, comprising a substantially rigid barrier about the edge of the diaphragm so that sound waves from one side will be prevented to a considerable extent from reaching and interfering with those emitted from the other side.

40 Another feature of the invention resides in the method of supporting the vibratory element. The ordinary diaphragm or cone which is attached to its support by inflexible means or by means possessing an appreciable amount of restoring action will respond very well to the intermediate and higher frequencies within the range of audibility but it either fails to respond altogether to the lower frequencies or responds so feebly to them that 45 small intensity of sound only is obtainable and considerable distortion is introduced into the speech or music being reproduced. The present invention contemplates attaching the diaphragm or cone to its support by springs 50

or flexible means which have minimum possible elastic restoring action, such action being just sufficient to maintain the element in its normal rest position and restore it to this position when it has been displaced. In this respect it is analogous to a so called "dead beat" instrument whose moving element will move to a certain position and then stop dead without any appreciable overthrow. In the present case the diaphragm or cone will be returned to its normal rest position by just sufficient restoring force to cause it to reach its rest position and there will be substantially no overthrow.

55 An element supported in this manner and hereinafter referred to as a freely supported body will have its restoring force confined almost wholly to the supporting means itself and will have two distinct modes of operation within the range of audibility. At the lower 60

5 frequencies where the wave lengths are large it will vibrate not unlike a piston, that is the whole surface of the element will move with substantially equal amplitude and in substantially the same phase, thus giving faithful sound reproduction for even the lowest audible frequencies. At the intermediate and higher frequencies however the free supported vibrating element no longer acts as a 10 piston but vibrates as an ordinary diaphragm with a free instead of a clamped boundary; that is the displacements from rest position set up at its center will travel to its edge and back again to the center causing flexure of 15 the element and setting up sound waves in the usual manner. As the piston action is obviously well suited to the reproduction of low frequency sounds and as the diaphragm action is well suited to the reproduction of 20 high and intermediate frequency sounds it will be clear that this device will respond to all frequencies within its range in a manner admirably adapted to the particular frequencies being reproduced and that consequently there will be a more uniform response 25 over the complete range of audibility, resulting in a very faithful reproduction substantially free from distortion.

30 A more complete understanding of the invention may be had from the following detailed description which should be read in connection with the accompanying drawings in which

35 Fig. 1 shows a specific embodiment according to the invention,

Figs. 2 and 3 a section and elevation respectively of a modification and

40 Fig. 4 shows a plurality of curves illustrating the action of the freely supported vibratory element.

45 In Fig. 1 is shown a cabinet comprising a base 2, sidewalls 3 and 4 and top 1. This cabinet may include a radio receiver, electric phonograph or similar device indicated diagrammatically at A and B, it being understood that the output circuit of this device represented by wires 14 has undulating currents therein corresponding to sounds which it is desired to reproduce from the vibrating system. The side wall 4 of the cabinet has an aperture 15 formed therein which should preferably be as large as possible. This aperture is covered by the grille 5 supported by suitable brackets on the sidewall 4. Within 50 the aperture 15 is supported the vibratory element or diaphragm 6 from whose vibrations result the sounds corresponding to electric currents in the wires 14. The element 6 is supported by springs 8 attached to lugs 7 on the vibratory element and to lugs 9 in the sidewall 4 thus providing a slightly resilient support for the vibratory element.

55 The vibration of the element 6 is caused in the example shown by the electromagnetic device 12 whose coils are connected to the out-

put conductors 14. This magnetic device as shown consists of a permanent magnet having electromagnets associated therewith, but it is obvious that other actuating means, such as the balanced armature or electrodynamic types, for example could readily be used. These devices are well known in the art and therefore further description of them is unnecessary. To the vibratory element 6 is fastened an armature 10 responsive to the magnetic field of the device 12. The armature 10 is fastened in any suitable manner to the element 6 by adjusting means including a thumb screw 11 by which its position with respect to the magnetic device 12 may be varied, thereby controlling the response of the vibratory element to the magnetic device. The magnetic device is supported from the base 2 by the bracket 13, although obviously any other convenient method of support could be adopted.

60 The supporting springs 8 should be made as light as possible as their purpose is to support the diaphragm with minimum possible elastic restoring force. They should therefore possess just sufficient resiliency to maintain the element 6 in its normal rest position and restore it to this position without appreciable overthrow when it has been displaced. When these conditions are satisfied 95 this vibrating element alone will have a natural frequency below its operating range that is below the range of audibility, and in responding to the lower audible frequencies substantially as a vibrating piston it will reproduce low frequency sounds faithfully without appreciable distortion. The intermediate and higher frequencies in the audible range will cause the element 6 to operate as a vibratory diaphragm in the well known manner and its natural characteristics will make the piston action negligible at these frequencies according to well known physical laws.

65 The action of a body thus supported will be clearer after a consideration of the curves shown in Fig. 4 in which abscissas represent frequency and ordinate a function of the sound intensity which for lack of a better name has been designated as diaphragm response. The audible frequencies in this graph extend from the point A to the point C and the response of the body acting as a piston has been represented by curve P and its response as a true diaphragm by curve D. The diaphragm response necessary to give faithful and substantially distortionless reproduction of sound has been designated by the dotted line E E, that is any diaphragm response which deviates from this line may be considered as undesired operation and any response which is similar to it may be considered as desirable operation. This is of course only an approximation as in practice the change over from desirable to un-

desirable operation will not occur for a definite type of response but will be gradual. The closer the actual curve approximates the line E E the more satisfactory will be the performance. This approximation, however, is close enough to the actual operation to assist in understanding the actual conditions. Returning now to the curves it is apparent from curve D that if the vibratory element 5 acted as an ordinary diaphragm throughout the audible range there would be very good sound reproduction in the region from B to C but very poor reproduction in the region from A to B. There would then be very 10 desirable reproduction of the intermediate and higher frequencies but very poor reproduction of the lower frequencies. From an examination of the curve P, representing the action of a vibratory element as a true piston 15 that is such reproduction as depends on the movement of the diaphragm as a unit to cause all sound waves, it will be obvious that a vibratory element with piston action would give very good reproduction in the region from A to B but very poor reproduction in the region from B to C. In other words the vibratory piston would reproduce the lower frequencies very well but the intermediate and higher frequencies very poorly. 20 A freely suspended body such as a diaphragm supported as explained above partakes of the nature of a piston as well as a diaphragm. At the lower frequencies the piston action will predominate and at the intermediate frequencies the diaphragm action will predominate and the resultant response curve will be somewhat of the form P.—F.—D. From this it will be seen that the freely suspended element will reproduce faithfully, without undue distortion and with desirable intensity all frequencies within the audible range covering entirely the region from A to C. 25 The structure shown in Fig. 1 possesses further advantages in that the walls of the cabinet, particularly the portions of the side wall 4 surrounding the aperture act as a baffle to prevent interference between the sound waves leaving the front of the diaphragm and those emitted from the rear. 30 These two sets of waves on leaving their respective sides of the diaphragm will be 180° out of phase; that is as a wave of condensation is emitted from the front face a wave of rarefaction will simultaneously leave the rear face. These waves spread out in all directions and, if the vibrating element were not surrounded by some baffle means, it is obvious that the waves from its rear face would 35 reach the area covered by waves from its front face considerably out of phase with the latter and thereby cause considerable distortion and diminution of sound intensity. This may be corrected by providing a rigid barrier around the acoustic element so that 40

the waves from the rear face will be cut off from the area in front of it altogether or so that the path through which they must travel to reach this area will be so lengthened that their effects in interfering with the waves emitted from the front face will be negligible. In the present structure the wall 4 surrounding the vibrating element acts as a rigid barrier or baffle cutting off the waves emanating from the rear of the element from the area in front of it. Maximum sound intensity and minimum distortion is therefore obtained from the sound waves emitted by the front of the vibratory body. 45 A modification of the device is shown in Figs. 2 and 3 which is entirely analogous in its operation and possesses all the advantages of that shown in Fig. 1 but which differs from the latter in that the loud speaker is a separate unit and not incorporated in the cabinet of an associated radio receiver or similar device. Referring to these figures the reference numeral 20 designates a base on which is mounted the vibrating element 22 shown as of the double cone type and supported by a flat ring 21 to which it is attached by strips 23, which may be of flexible material such as rubber or leather or slightly resilient material as metal. The strips 23 are secured to the ring 21 by suitable clamping members 24. 50 While four of these attaching members have been shown in the present instance it is obvious that more or less could be used as desired. In some cases a single one at the top may be sufficient while in other cases an annulus of soft leather or rubber completely closing the space between the cone element and the supporting ring may be desirable. Whatever form of attachment is chosen however it must possess substantially the same properties as to its restoring characteristics as the springs 8 in Fig. 1. That is the system must possess just sufficient elastic restoring force to maintain the cones in normal rest position and to 55 return them to this position when they are displaced therefrom. As long as these conditions are satisfied it is evident that the cones will behave as a freely suspended body and act substantially as a piston in response to low frequencies and as an unclamped diaphragm in response to intermediate and high frequencies as explained in connection with the device in Fig. 1. 60 The supporting ring 21 is attached to the base 20 and held upright thereon by means of brackets 27. The operating mechanism 25 is supported on a bracket 26 and has an operating rod 28 fastened to the double cone 22 as shown. It is immaterial what particular form of operating mechanism is used, it being only essential that it be of such a character as to impart vibrations to the rod 28 corresponding to those of the original sound being reproduced. 65

The device shown in Figs. 2 and 3 is not 70

enclosed in a cabinet and therefore the supporting ring 21 must be of sufficient width to act as a baffle for preventing the sound waves emitted from the rear of the cone member 5 from interfering with those emitted from the front. It will probably be necessary to make it with an outside diameter of perhaps two feet for the large cones now in use. If desired however the operating mechanism of this 10 device can be enclosed in a casing in which case the supporting ring 21 can be replaced by one wall of the casing making the structure very similar to that in Fig. 1.

While I have disclosed the invention in several particular forms it will be obvious to those skilled in the art that it is capable of many modifications, for example, the modification shown in Figs. 2 and 3 can be used in connection with a radio cabinet as that in 20 Fig. 1 and the vibratory system of Fig. 1 can be used as a unit as suggested in Fig. 2. Moreover the vibrating elements need not be limited to the forms shown but can be of any other shape or style as long as their supporting 25 system possesses the characteristics explained above. I intend to be limited in the invention therefore only as indicated in the following claims.

Having described my invention, I claim:

30 1. In an acoustic device the combination of a vibratile body, means for vibrating said body, a supporting member, and means for suspending said body from said supporting member, said suspending means having the minimum amount of restoring action which 35 will return said body to its position of rest when moved therefrom by the vibrating means.

40 2. In an acoustic device the combination of a vibratile body, a supporting member, a plurality of springs for positioning said body in a predetermined position with respect to said member, and means responsive to operating forces for moving said body 45 from said predetermined position against the action of said springs, said springs having the minimum amount of resiliency necessary to restore said body to said predetermined position when no operating forces are 50 acting on said body.

55 3. In a device for reproducing sound the combination of a diaphragm, a supporting member forming an opening slightly larger than said diaphragm, means connected between the periphery of said diaphragm and said supporting member for holding said diaphragm in its inoperative position, and a driving unit for moving said diaphragm from its inoperative position in response to 60 operating forces, said means having a minimum restoring action to return said diaphragm to its inoperative position when no operating forces are acting upon it.

65 4. In a device for reproducing sound the combination of a diaphragm having a cir-

70 cular periphery, a member forming a circular aperture slightly larger than the periphery of said diaphragm, a plurality of lugs fastened to said diaphragm near its periphery, a corresponding number of lugs fastened to said member adjacent to said aperture, springs fastened between the lugs on said diaphragm and the lugs on said member for supporting said diaphragm in its inoperative position, and means responsive to 75 operating forces for moving said diaphragm from its inoperative position, said springs having a minimum restoring action to return said diaphragm to its inoperative position when no operating forces are acting 80 upon it.

5. A sound reproducing device comprising a vibratile diaphragm, a support, and means comprising a thin, flat, flexible strip for connecting the diaphragm and the support whereby the diaphragm has freedom of vibration.

6. A sound reproducing device comprising a vibratile diaphragm, a support, thin, flat, flexible elements secured to the edge of said diaphragm and to said support for holding the diaphragm in a free vibratile position.

7. A sound reproducing device comprising a vibratile diaphragm, a support, said diaphragm having its edge spaced from said support, thin, flexible strips in the space between said edge and said support and connected to said edge and said support for supporting the diaphragm for free vibrations thereof.

8. A sound reproducing device comprising a vibratile diaphragm, a support surrounding the same and spaced from the edge thereof, spaced flexible elements in said space, means for securing said elements to the edge of said diaphragm, and means for securing said elements to said support, whereby said diaphragm has substantially free vibration.

9. Sound reproducing apparatus comprising a cabinet having side walls forming an enclosure with the top and bottom thereof, an opening of material size in one of said side walls, a grille covering said opening, a sound reproducer of the diaphragm type housed within said cabinet with the diaphragm thereof adjacent said opening, said diaphragm being sufficiently large to reproduce sound without the aid of a horn, a radio receiver housed within said cabinet, and connections from the output of said radio receiver to said sound reproducer.

10. A sound reproducing device comprising a vibratile diaphragm, a structure spaced from said diaphragm, spaced flexible elements of substantially thin, flat material, means for connecting said elements to said diaphragm, and means for connecting said elements to said structure.

11. A sound reproducing device comprising a vibratile diaphragm having a sub-

stantially conical surface, a structure spaced from said diaphragm, spaced flexible elements of thin, flat material extending outwardly from said diaphragm to said structure, means for connecting one end of each of said elements with said diaphragm, and means for connecting the other end of each of said elements with said structure.

12. Sound reproducing apparatus comprising a cabinet, radio receiving apparatus housed within said cabinet, an opening in said cabinet, a loud speaker electrically connected with said radio receiving apparatus and housed within said cabinet with its diaphragm adjacent to said opening, said loudspeaker including a diaphragm sufficiently large to reproduce sound at loudspeaker volume without the aid of a horn, supporting means adjacent to said opening, and flexible suspending means having a low restoring force connected between said supporting means and said diaphragm, whereby said diaphragm is supported substantially adjacent to said opening.

13. Sound reproducing apparatus comprising a cabinet having a wall, an opening of material size in said wall, a loudspeaker including a diaphragm and operating means therefore housed within said cabinet, said diaphragm being sufficiently large to reproduce sound at loudspeaker volume without the aid of a horn, radio receiving apparatus housed within said cabinet, electrical connections from said radio receiving apparatus to the diaphragm operating means, supporting means adjacent to the opening in said wall, and flexible suspending means having a low restoring force connected substantially between the peripheral portion of said diaphragm and said supporting means whereby the periphery of said diaphragm is positioned adjacent to said opening but spaced therefrom.

14. Sound reproducing apparatus comprising a cabinet, radio receiving apparatus housed within said cabinet, an opening in said cabinet, a loudspeaker electrically connected with said radio receiving apparatus and housed within said cabinet with its diaphragm adjacent to said opening, said loudspeaker including a diaphragm sufficiently large to reproduce sound at loudspeaker volume without the aid of a horn, supporting means for the diaphragm having a low restoring force and operating means for the diaphragm housed within said cabinet.

15. Sound reproducing apparatus comprising a cabinet having a front wall, an opening of material size in said front wall, a loudspeaker including a diaphragm and a driving unit housed within said cabinet, said diaphragm being sufficiently large to reproduce sound at loudspeaker volume without the aid of a horn, supporting means adjacent to said opening in the front wall,

and flexible suspending means having a low restoring force connected substantially between the peripheral portion of said diaphragm and said supporting means whereby the periphery of said diaphragm is positioned adjacent to said opening.
